JOSEPH GOTTLIEB, OF BOSTON, MASSACHUSETTS.

Letters Patent No. 72,630, dated December 24, 1867.

IMPROVED TASSEL-CLAMP FOR WINDOW-CURTAINS.

The Schedule referred to in these Letters Patent and making part of the same.

TO ALL PERSONS TO WHOM THESE PRESENTS MAY COME:

Be it known that I, JOSEPH GOTTLIEB, of Boston, in the county of Suffolk, and State of Massachusetts, have made a new and useful invention, having reference to the attachment of a "Down-Haul Tassel to the Curtain or Shade of a Window;" and I do hereby declare the same to be fully described in the following specification, and represented in the accompanying drawings, of which—

Figure 1 is a front elevation, and

Figure 2 a vertical and transverse section of a tassel and window-shade with my invention applied thereto.

The purpose of the invention is to enable the tassel to be either readily affixed to or removed from the lower part and bar of the shade.

In the common way, heretofore practised, of attaching a "down-haul tassel" to a window-shade, the cord of the tassel was run through the hem and the stick or bar of the shade, and afterwards tied in a knot.

After separation of the parts for the purpose of enabling the shade to be washed, and washing the shade, it has generally been found difficult to bring the holes in the hem in proper coincidence with the hole in the stick or bar placed within the hem, attempts to accomplish such being generally attended with more or less tearing of or injury to the shade.

With my invention no hole through the shade or bar thereof is requisite. In carrying out my said invention, I attach the curtain-cord to the shade by means of a jawed clamp to embrace the curtain-hem and the bar.

In the drawings, A denotes the shade or curtain, of which *a* is the hem, and *b* the bar or stick placed within such hem. B is the tassel, of which *c* is the cord, and C the jawed clasp fixed to the upper end of the cord. The said clasp consists of two jaws, *d d'*, united together, so as to be capable of being easily moved either away from or toward each other. A rod or wire, *e*, bent twice, at a right angle, or thereabouts, in manner as represented in fig. 2, is attached at one end to one of the jaws, and passes through a hole in the other jaw, and has a screw cut on the part projecting beyond the latter jaw. A clamp-nut, *f*, is screwed upon such screw, and serves, with the screw-wire *e*, to clamp the jaws upon the curtain-hem and its bar.

By bending the clamp-wire, in manner as described, it forms a stop to prevent the screw-nut from forcing the jaws too closely together, so as to injure their connection when they and such connection are made in one piece of sheet metal. Each of the jaws should be provided with spurs or claws, as shown at *h h h*.

I claim the clasp, made as described, viz., with the clamp-wire bent and arranged and combined with the two jaws, in manner as explained.

JOSEPH GOTTLIEB.
